UNITED STATES PATENT OFFICE.

DE LANCY W. SMITH, OF PUEBLO, COLORADO, ASSIGNOR TO LINKO MOTOR ASSOCIATION, OF PUEBLO, COLORADO, AN ASSOCIATION OF COLORADO.

DESIGN FOR A BADGE OR EMBLEM.

60,578.

Specification for Design.

Patented Mar. 7, 1922.

Application filed February 23, 1921. Serial No. 447,325. Term of patent 3½ years.

To all whom it may concern:

Be it known that I, DE LANCY W. SMITH, a citizen of the United States, residing at Pueblo, in the county of Pueblo and State of Colorado, have invented a new, original, and ornamental Design for Badges or Emblems, of which the following is a specification, reference being had to the accompanying drawing, forming a part thereof.

I claim:

The ornamental design for a badge or emblem as shown.

DE LANCY W. SMITH.
